COMBINED DOOR LOCK AND ESCUTCHEON PLATE

Fred Kaiser, New York, N. Y.

Application November 7, 1957, Serial No. 48,369

Term of patent 14 years

(Cl. D10—8)

Figure 1 is a perspective view of a combined door lock and escutcheon plate, showing my new design, the same being in an unlocked position thereof.

Figure 2 is a front elevational view of Figure 1.

Figure 3 is a plan view of Figure 1.

Figure 4 is an end elevational view as seen from the left of Figure 1 in unlocked position.

Figure 5 is an end elevational view as seen from the right of Figure 1 in locked position.

The dominant features of the design reside in the portions shown in full lines.

I claim:

The ornamental design for a combined door lock and escutcheon plate, as shown and described.
